UNITED STATES PATENT OFFICE.

FERDINAND STRAUSS AND OTTO R. STARKE, OF NEW YORK, N. Y., ASSIGNEES TO THE FERDINAND STRAUSS CORPORATION, OF NEW YORK, N. Y., A CORPORATION OF NEW YORK.

MECHANICAL TOY.

Application filed February 1, 1926. Serial No. 85,187.

This invention relates to mechanical toys and has for its main object the provision of a toy inexpensive and substantial in construction, and one that will afford amusement to children.

Another object of the invention is to provide a toy in the shape of a zeppelin that is adapted to simulate an aviator having lost control of his machine.

10 Other objects and novel features of construction will become more apparent and will be fully described as the specification proceeds.

In the drawings forming a part of this 15 specification,

Fig. 1 is a side view in elevation of a toy zeppelin showing the invention as applied thereto.

Fig. 2 is a top plan view of the driving 20 mechanism of the same and

Fig. 3 is a detail view showing the aviator mounted on the winding key.

Referring to the drawings in detail 5 indicates a body of a toy in the shape of a zeppelin to which is suitably secured a frame work 6 containing therein the usual drive or motor mechanism 7, comprising a winding key 8, power spring and controlling means 9, drive gear 10 suitably mounted on

25 the key 8; a pinion 11 in mesh with the gear 10 is mounted on a square shaft 12 at approximately the centre portion thereof, a segmental gear 13 is secured to the lower end of the shaft 12 and meshes alternately 30 with pinions 14 and 15, pinion 14 is secured to a shaft 16 having a ground engaging wheel 17 fixed thereto, while pinion 15 is loosely mounted on the shaft 16 and has a ground engaging wheel 18 fixed thereto.

40 At the rear of the body 5 there is pivotally mounted a forked lever 20 to which is journaled a wheel 21; a similar fork 22 having a wheel 23 journaled therein is pivotally mounted at the front of the body 5. On 45 the shaft 12 there is removably mounted a figure 24 in the shape of an aviator whose head 25 is loosely mounted on a pin 26 passing through the body of the aviator 24, having arms 27 thereon and a steering wheel 50 28 in the hands of the aviator.

To operate the toy the motor is wound up and the toy is placed on the ground with the wheels 17, 18 and 21 in engagement with the ground, the toy will be propelled forwardly as long as the segmental gear 13 is

in mesh with the pinion 14. As soon as the gear 13 becomes disengaged from the pinion 14 and engages pinion 15 the body 5 will tip downwardly at the front, wheel 23 will engage the ground and the entire toy will pivot on the loosely mounted wheel 18 and describe an arc of approximately 180 degrees. This action will be repeated until the spring 9 is unwound. It will also be seen that the figure 24 being mounted on the shaft 12 will intermittently describe two semi-circular movements to each revolution of the shaft 12, and the head 25 will wabble on its pivot 26 due to the alternate impact of the gear 13 with the pinions 14 and 15. 60 The aviator body 24 may be placed on the upper portion 30 of the key shaft 8 and used as a winding key to wind the motor from the top as shown in Fig. 3. In this case the number of times that the aviator 65 will turn during one revolution of the gear 13 will be increased.

From the foregoing it will be seen that we have provided a toy that will amuse children by the different antics it goes 70 through, such as going forwardly, dipping forwardly or backwardly, going around in circles and by the different movements of the aviator.

The tipping action referred to is due to 75 the alternate impact of the pinions 14 and 15 with the gear 13, and to the fact that when either the front or rear ground engaging wheel is in contact with the ground, the other one will be raised above the 80 ground, and the body, which is loosely mounted on the shaft 16 will tip alternately in opposite directions at each impact of the pinions and the gear.

Having thus described our invention, 85 what we now claim is:

1. A mechanical toy of the class described, comprising a body, a motor within the body, a drive gear within the motor, a pinion in mesh with the drive gear, a shaft associated 100 with the pinion, a segmental gear on the shaft, a ground engaging wheel fixed to said pinion, a shaft to which said pinion and wheel are fastened, a second pinion adapted to mesh with the segmental gear, a ground engaging wheel fixed to said second pinion said wheel and pinion being loosely 105 mounted on said shaft, and a figure on the segmental gear shaft adapted to be intermittently actuated to describe an arc. 110

2. A mechanical toy of the class described, comprising a body, a motor within the body, a segmental gear forming a part of said motor, a plurality of pinions intermittently in mesh with the segmental gear, a ground engaging wheel associated with each of said pinions, a shaft in fixed relation with one pinion and wheel and in loose relation with the other pinion and wheel, a pivotally mounted wheel at the rear of the body and a like pivotally mounted wheel at the front of the body adapted to alternately engage the ground.
3. A mechanical toy of the class described, comprising a body, a motor within the body, a winding key shaft associated with the motor, a drive gear on the key shaft, a pinion in mesh with the drive gear, a shaft upon which the pinion is mounted, a portion on the key extending beyond the drive gear and a figure arranged to be removably and rotatably mounted on either the pinion shaft or on the key shaft extension.
4. A mechanical toy of the nature described, comprising a body, a motor within the body, a drive gear on the motor, a shaft rotatably mounted in the body, a segmental

gear on the motor, a plurality of pinions on the shaft alternately in mesh with the segmental gear to reverse the direction of the toy, a vertical shaft rotated by the drive gear, and a figure rotatably mounted on the vertical shaft and intermittently revolved therewith due to the reversal in direction of the movement of the toy.

5. A mechanical toy of the nature described comprising a body, a motor within the body, a drive gear on said motor, a shaft revolvably mounted in the body, a pinion mounted upon the shaft in mesh with the drive gear, a segmental gear mounted on the shaft, a shaft revolvably journalled in the body, a pair of pinions on the second mentioned shaft alternately meshing with the segmental gear, and a figure mounted on the first mentioned shaft intermittently rotated by the segmental gear due to the alternate meshing of the pinions with the segmental gear.

In testimony whereof we hereunto affix our signatures.

OTTO R. STARKE.
FERDINAND STRAUSS.
